UNITED STATES PATENT OFFICE.

ELLIOTT G. FLETCHER, OF SOUTHEND-ON-SEA, ENGLAND, EXECUTOR OF CHARLES LENI,
DECEASED.

CASH-REGISTER.

No. 860,740.

Specification of Letters Patent.

Patented July 23, 1907.

Application filed November 7, 1904. Serial No. 231,805.

To all whom it may concern:

Be it known that I, ELLIOTT G. FLETCHER, a subject of His Majesty the King of Great Britain, and a resident of Southend-on-Sea, in the county of Essex, England, and the executor to the last will and testament of CHARLES LENI, in his lifetime of Southend-on-Sea, aforesaid, and that the said CHARLES LENI did invent a new and useful Improvement in Cash-Registers, of which the following is a specification.

10 This invention relates to a cash register of the type wherein the amount of a customer's purchase or equivalent transaction is inscribed upon a recording paper, the object of such invention being to provide a very simple and inexpensive form of cash register specially 15 suitable for small shop-keepers and others, whereby a correct record can be kept of all cash sales and at the same time the customers can see the amount of their individual transactions recorded.

In order that my said invention may be the more 20 readily understood and carried into practical effect, reference is hereby made to the accompanying sheet of 25 illustrative drawings, wherein:

Figure 1 is a vertical section of the cash register mounted upon a till with the till in its closed position.

25 Fig. 2 is a plan view thereof, while, Fig. 3 is a plan view with the till in its open position.

Referring to the drawings, wherein like letters of reference indicate corresponding parts wherever occurring, A indicates the case of suitable dimensions and 30 constructed of wood or other suitable material, such case having three vertical sides, while the front side or face a is given an angle of about 45 degrees, and is hinged at a' to permit of access to the interior.

Upon the top of the case A I provide a clock b to enhance the appearance of, and increase the usefulness 35 of the device, while in the face a there is provided an opening (or a plurality thereof) c, for the purpose of enabling a recording roll of paper (hereinafter referred to) to be inscribed upon therethrough. A part of this 40 opening c may be glazed, as at c'.

Within the upper part of the case A I mount a feed roller d in suitable bearings in the sides of such case, which roller has rolled thereon a web of suitably ruled paper e, one end of which is carried over a flat support 45 f and wound upon a record roller g mounted in bearings h in the sides of the casing A, near the lower end thereof.

Upon one end of the lower roller g I provide a toothed-wheel g¹ which toothed-wheel may be keyed to, or formed integral with, such roller, the said wheel being 50 arranged to gear with a pinion i, rigidly mounted upon a spindle i', mounted in the sides of the case A to the rear of the roller g, one end of such spindle projecting through the coincident side of the said casing and be-

ing provided with a suitable device, such as the handle i², to allow of it being rotated by the operator. It 55 will be understood that when motion is imparted to the spindle i¹, the roller g is rotated through the connection of the gear wheel g¹ and pinion i and the paper e is caused to pass in front of the inscribing opening c and to be rolled upon the record roller g. To prevent 60 retrograde movement of the aforesaid rollers and consequently the recording paper, I provide a pawl j, which is pivoted at j¹ to one of the sides of the case A, the nose of such pawl being adapted to engage with side projections g² (or they may be teeth) on the 65 toothed-wheel g¹ when it is attempted to give the roller g a retrograde motion.

It will thus be seen that after the amount of the purchase or similar transaction has been entered upon the paper e, through the inscribing opening c of the 70 case A, the rollers aforesaid are caused to be rotated in the foregoing manner, which causes the web on the top roller d to be unrolled to a desired extent and a corresponding length to be rolled upon or taken up by the lower roller g, while it naturally follows that the 75 inscribed portion of the said paper is caused to pass from view behind the front of the case. The arrangement of the pawl j aforesaid prevents any attempt upon the part of the salesman or other individual using the register to reverse the motion of the rollers and recording paper for the purpose of making alterations or erasures in the previous entries on the latter.

The hinged face a of the case A is provided with a suitable lock k for preventing unauthorized access to the interior of the cash register.

The apparatus may be arranged to stand upon a counter or the like, or it may be mounted in or upon a suitable drawer or upon a stand provided for the purpose.

In the drawings the apparatus is shown revolvably mounted upon a till designed to stand upon a counter 90 in such a way that when the entry has been made by the assistant upon the record strip the opening of the till causes the casing A to partially revolve, so that the front of the register faces the customer, who can then see that the correct entry has been made. The closing 95 of the till returns the apparatus to its normal position. In order to effect this the casing A is fixed upon a short spindle l which is held to revolve in a bearing l' arranged in the top of the till m. Upon the lower end of the spindle l a toothed wheel or pinion l² is 100 keyed while the till m is provided with a rack m¹ arranged to mesh with the toothed wheel or pinion l².

It will be readily understood that the drawing out of the till in the direction of the arrow B will cause the pinion l² to revolve a half-turn in the direction of the 105 arrow B¹ carrying the casing A with it, while the clos-

ing of the till will cause a reversal of the movement and the apparatus will be returned to its normal position. Ball bearings n may if desirable be interposed between the casing A and the till m .

5 What I claim and desire to secure by Letters Patent of the United States is:

1. In a cash register and till the combination of a case having a hinged face and an inscribing opening therein partially glazed, and a narrow transverse support or desk 10 for the usual recording web to pass over, said support facilitating the inscribing on the web by the user; with means for causing the said register to partially revolve to face the customer when the till is drawn out, said means consisting in a revoluble spindle mounted in the cash 15 till, the cash register being fixed upon the end of said spindle; a fixed pinion on the lower end of said spindle; a rack carried by the till and arranged to gear with said

pinion, and ball bearings interposed between the cash register and the cash till, substantially as specified.

2. The combination with a cash till and a cash register 20 of a short spindle revolvably held in bearings in the upper part of the cash till, the cash register being fixed upon the upper end of the revoluble spindle, a pinion keyed upon the lower end of the said spindle, a rack carried by the cash till substantially as specified.

In testimony whereof I have signed my name to this specification in the presence of two subscribing witnesses.

ELLIOTT G. FLETCHER,
Executor of the estate of Charles Leni, deceased.
